UNITED STATES PATENT OFFICE.

FREDUS A. THURSTON, OF CHICAGO, ILLINOIS.

SPARK-PRODUCING DEVICE.

No. 839,049.

Specification of Letters Patent.

Patented Dec. 18, 1906.

Application filed February 7, 1906. Serial No. 244,629.

To all whom it may concern:

Be it known that I, FREDUS A. THURSTON, a citizen of the United States, residing at Chicago, in the county of Cook and State of Illinois, have invented a certain new and useful Improvement in Spark-Producing Devices, of which the following is a full, clear, concise, and exact description, reference being had to the accompanying drawings, forming a part of this specification.

My invention relates to spark-plugs for explosive-engines for use in motor-vehicles, launches, and the like.

Prominent objects of the invention are to provide a simple, practical, and inexpensive form of spark-plug; to secure reliability and effectiveness of action, particularly with the device in a horizontal or inclined position; to prevent injury of any kind to the operating parts of the device either by heat, gas, or water or otherwise; to secure a large and bright flash; to procure very high efficiency of action, and to secure the foregoing and other desirable results in a simple, practical, and effective manner.

In the accompanying drawings, Figure 1 is a longitudinal section of a spark-plug embodying my invention. Fig. 2 is an end view of the device; Fig. 3 is a section taken on line 3-3 in Fig. 1, and Figs. 4 and 5 are views of details of construction.

The spark-plug shown in the drawings for carrying out my invention, comprises a shell or casing 1, conveniently of cylindrical form and made open at both ends. One end A is preferably threaded, as at 2, to permit the device to be readily screwed into and out of the cylinder of the engine or other device in which the plug is to be used. Within the shell or casing 1, which is desirably formed of metal, such as brass or iron, is a spool or bobbin, on which is wound a coil of fine wire 3. The bobbin is desirably made of metal—as, for example, of iron or steel—and consists of a central spindle 4 and a pair of end flanges 5 and 5^a, which are but very little smaller than the interior of the shell or casing 1. A layer 6 of insulating material, preferably fireproof also—as, for example, asbestos—is arranged immediately outside of the spindle 4 of the bobbin, and layers 7 and 8 of the same or similar material are arranged inside of the flanges 5 and 5^a of the bobbin. A layer 9 of the same or similar material is arranged between the coil of wire 3 and the shell 1 and layers 10 and 11 at each end of said bobbin. On the layer 10 of as-

bestos is spread a thin coat 11 of cement or similar material, on which is laid a thin metal plate 12, thereby forming a metallic covering or protection for the asbestos 10. The entire bobbin with its coil of wire is thus inclosed in asbestos or similar material, thereby insulating it both electrically and thermally from the shell 1, and at the same time the coil of wire 3 is similarly insulated from the bobbin. Against the plate 12 rests an annular metal ring 13. The spool with its asbestos covering fits tightly within the interior of the shell or casing 1, and the ring 13 fits tightly at the end of the spool, whereby the parts are held in position and a tight and compact structure is formed, and at the same time the coil of wire is thoroughly protected from gases, water, and heat in the cylinder to which the plug may be attached. In my present invention I have shown a ring 13 for holding the parts in position, although it is obvious that the end of the casing 1 could be provided with a flange in place of the ring 13.

A pin 14 is secured to the flange 5^a of the bobbin, being desirably screw-threaded and screwed into said flange. The plate 11 is provided with insulation 15, surrounding the pin 14.

A ring or collar 16 is inserted in the end A of the casing 1 against the metal plate 12 and inside of the ring 13, the ring having a cut-away portion to accommodate the pin 14. The inner edge or face 17 of the ring 16 is inclined or beveled. An armature 18 is arranged within the ring 16 and adapted to vibrate toward and away from the magnet. A lug 19 is formed on the inner face of the armature 18 to prevent it from sticking to the plate 12, and a lug 20 is also provided on the outer face of said armature. The lug 20 strikes against the bent end of the pin 14 and makes contact therewith to close the circuit through the device.

When the magnet is energized, the armature 18 is attracted, so that it separates from the pin 14 and opens the circuit, creating a spark. This opening of the circuit deenergizes the magnet, releasing the armature 18, whereupon the latter falls back, so as to make contact with the pin 14 again. This closes the circuit again, causing the magnet to be reenergized and the armature again attracted and another spark created. This action, causing a series of sparks, continues as long as the circuit is closed. The return of the armature to normal position is caused and

insured by its arrangement in connection with the ring 16. The latter supports the armature at one side of its center of gravity, so that it tends to fall out and against the contact 14, even though standing vertically. The ring 16, being an annular support, will support the armature no matter what position the plug happens to be turned to.

The end B of the casing 1 is screw-threaded and provided with a metal plug or cap 21, which screws into said casing. In this cap 21 is an opening through which is inserted a threaded pin or spindle 22, on the inner end of which is a nut 23, the outer end being provided with two nuts 24 and 25. There is also provided on the pin or spindle 22 between the nuts 23 and 25 and held firmly in place thereby an insulating ring or bushing 26, preferably of lava or similar material, which ring 26 is of sufficient thickness to completely fill the space between the pin 22 and hole in the cap 21, thereby holding the pin firmly in place in said cap. One end 27 of the wire forming the coil 3 is connected with the pin 22, preferably by clamping between the nut 23 and bushing 26, and the other end of said coil is connected with the metal bobbin. One side of the battery is connected with the pin 22 by the nuts 24 and 25 and the other is connected with the engine-cylinder or some other part of the engine. Thus the circuit is made from the pin 22 to the coil 3, thence by the bobbin to the pin 14, and thence by the armature 18 to the shell 1 and engine-cylinder to battery. When the armature 18 is attracted by the energization of the coil 3, said armature is separated from the pin 14, thereby opening the circuit and allowing the armature 18 to fall back against the pin 14 to thereby close the circuit again. Thus a continual vibratory action of the armature is set up with the result of formation of sparks due to the self-induction at make and break.

45 The device is very simple and practical, and in addition to the above-mentioned advantages of being thoroughly protected from

heat, gases, and water and being well insulated electrically it is very efficient, requiring but a small percentage of the usual amount 50 of battery employed in devices of this kind, and, furthermore, it is particularly adapted for use in a horizontal or inclined position.

It will be understood that changes and modifications can be made in the device herein described without departing from the invention.

What I claim is—

1. In a device of the class specified, the combination of an electromagnet, a loose armature, and an annular support which is arranged to support the armature at the inner side of its center of gravity.

2. In a device of the class specified, the combination of an electromagnet, a loose armature therefor, a contact for the armature on the outer side thereof, and a support for the armature, said support being adapted and arranged to engage and support the inner edge of the armature.

3. In a device of the class specified, the combination of an electromagnet having a vertically-disposed armature, and a device inclosing said armature and provided with a supporting edge, the armature having a 75 groove adapted to receive said edge and located at one side of the center of gravity.

4. In a device of the class specified, the combination of a horizontally-disposed electromagnet having a vertically-disposed armature, a ring inclosing the said armature and having an inclined face forming a supporting edge for said armature, the latter being provided with an annular groove to receive said edge, and said supporting edge being located on the side of the center of gravity of said armature nearest said magnet, and a contact opposite the armature.

In witness whereof I hereunto subscribe my name this 2d day of February, A. D. 1905, 90

FREDUS A. THURSTON.
